DESIGN FOR A TEXTILE FABRIC OR THE LIKE

Application filed October 11, 1932. Serial No. 45,291. Term of patent 3½ years.

To all whom it may concern:

Be it known that I, IRENE A. WEITZ, a citizen of the United States, residing at No. 1640 Ocean Avenue, borough of Brooklyn, city of New York, county of Kings and State of New York, have invented a new, original, and ornamental Design for a Textile Fabric or the like, of which the following is a specification, reference being had to the accompanying drawing, forming part thereof.

The figure is a plan view of a textile fab-

ric or the like, showing my new design, the dominant feature of which is the displaying of both sides of the flower petals.

The dot and dash lines on the drawing outline the design unit, which unit is repeated in staggered succession, as indicated by the angles A and B.

I claim:

The ornamental design for a textile fabric or the like substantially as shown and described.

IRENE A. WEITZ,
